UNITED STATES PATENT OFFICE.

CHARLES DICKINSON AND WILLIAM BELLAMY, OF NEWARK, NEW JERSEY.

ICE-PITCHER.

Specification of Letters Patent No. 23,455, dated April 5, 1859.

To all whom it may concern:

Be it known that we, CHARLES DICKINSON and WILLIAM BELLAMY, of Newark, in the county of Essex and State of New Jersey, 5 have invented a new and useful Improvement in Ice-Pitchers; and we do hereby declare that the following is a full, clear, and exact description of the same, reference being had to the annexed drawings, making 10 a part of this specification, in which—

Figure 1, is a vertical central section of our invention. Fig. 2, is a horizontal section of ditto, taken in the line x, x , Fig. 1.

Similar letters of reference indicate corresponding parts in the two figures.

To enable others skilled in the art to fully understand and construct our invention, we will proceed to describe it.

The pitcher is constructed of britannia 20 metal or other similar white metal or composition. The pitcher has double walls a, b , and is of the usual conical form, a space of requisite width being allowed between the walls to receive the filling c . The double 25 walls extend entirely around the pitcher, including both the lid d , as well as the bottom e , as plainly shown in Fig. 1. The nozzle f , however may be of single thickness, and a strainer g , may be placed and secured over 30 its lower end.

The filling c , is composed of one part calcined gypsum or plaster of paris, and three parts pulverized charcoal, mixed with water to a pasty consistency and in that state 35 placed between the walls of the pitcher. This composition, as it "sets" or hardens, expands, an effect due to the plaster of paris, and becomes firmly secured between the walls. It also becomes hard and very solid 40 and serves as a support to the walls a, b . The charcoal serves to lighten the mass, as its specific gravity is very little and at the same time the general properties of the plaster of paris are not destroyed by the ad- 45 mixture.

Plaster of paris, as is well known, is an excellent non-conductor of heat, and it also, after being mixed with water, becomes quite hard when dry, and expands in drying so 50 as to occupy more space than when mixed with water. The plaster of paris, therefore, it will be seen, possesses all the requisites for a proper filling, as it forms a very solid mass, protecting the walls of the pitcher

which would otherwise be liable to be 55 bruised or injured as britannia metal is quite a soft and ductile substance and readily bent or indented. There is however a serious objection to the use of plaster of paris alone in connection with britannia- 60 metal ware, and that is its weight. Britan- nia metal is quite heavy in itself, so much so that double-walled pitchers require to be made quite thin in order to have them suffi- 65 ciently light even when no filling is used. The weight of the metal therefore precludes the use of plaster of paris alone, as a filling; it has been used in some few instances, but abandoned for the reason above mentioned.

By adding three parts pulverized charcoal 70 to one of plaster of paris, the objection above alluded to is removed and a light and durable refrigerating pitcher obtained. The double walled pitchers without filling, and now in general use, soon become disfigured, 75 as the metal bends quite readily, and the slightest knock leaves an indentation. britannia metal or an equivalent composi- 80 tion is almost exclusively used for ice pitchers, as it forms a good body on which to plate by the galvanic process, and a great portion of the pitchers are plated. Even when not plated the metal or composition is susceptible of receiving a good polish, and very ornamental designs for pitchers are 85 got up. It is important therefore to retain the metal, and at the same time obtain some filling that will possess refrigerating prop- 90 erties and give the necessary solidity and durability with a requisite degree of light- 95 ness. We allege that by our invention, this object has been attained. Our improvement also enables us to employ walls composed of other metals or substances, very thin or brittle in their nature; because the filling 100 being hard, supports or distends the walls; so that if they are accidentally struck from within or without, they are not indented or broken when other pitchers would be. Thus our improvement enables us to make a 100 cheaper refrigerating pitcher than can be done by other methods, because less and lighter metal may be used; and it enables us to make a stronger pitcher because its double walls are braced and supported at all 105 points by a filling which is almost as solid as stone.

We do not claim, broadly, the making of

double-walled ice-pitchers, nor the interposition of a felt or woolen non-conductor between the walls. But

We claim, as an improved article of manufacture—

An ice-pitcher provided between its walls with a hard non-conductor, so as to protect the walls from indentation or fracture from

within or without, while it also assists refrigeration, as herein shown and described. 10
